UNITED STATES PATENT OFFICE.

ALBERT LOVELESS, OF ABERDEEN, WASHINGTON.

VALVE-SPRING-LIFTING DEVICE.

Application filed March 8, 1921. Serial No. 450,685.

To all whom it may concern:

Be it known that I, ALBERT LOVELESS, a citizen of the United States, and a resident of Aberdeen, in the county of Grays Harbor 5 and State of Washington, have invented certain new and useful Improvements in Valve-Spring-Lifting Devices, of which the following is a specification.

My invention relates to devices for lifting 10 the springs of poppet valves to permit the removal of the valve seat pins, such devices being commonly known as valve lifting devices.

The purpose of my invention is the provision of a valve lifting device by means of 15 which one or more valve springs can be readily compressed to disengaging position with respect to the valve seat pins, and maintained in such compressed position without necessitating the manual holding of any 20 portion of the device so that the operator's hands are free to withdraw the pins.

I will describe one form of valve lifting 25 device embodying my invention and will then point out the novel features thereof in claims.

In the accompanying drawings:

Figure 1 is a view showing in side elevation a portion of an internal combustion engine having applied thereto two of the valve lifting devices embodying my invention. 30

Figures 2 and 3 are vertical sectional views taken on the lines 2-2 and 3-3, respectively, of Figure 1.

Figure 4 is an enlarged detail perspective view of the yoke comprised in the device shown in the preceding views. 35

Figures 5 are enlarged detail perspective views of the spindle and nut comprised in 40 the device shown in the preceding views.

Figure 6 is a perspective view of one form of wrench adapted for the actuation of the nut of the device.

Similar reference characters refer to similar parts in each of the several views. 45

Referring specifically to the drawings and particularly to Figure 4, my invention in its present embodiment comprises a yoke designated generally at Y and formed of a metallic angle bar to provide a vertical portion 15 and a horizontal portion 16. The opposite ends of the vertical portion 15 have secured thereto by means of rivets 14, spacing blocks 17, while formed at regular spaced intervals 50 throughout the length of such portion are circular openings 18 which function as wind-

dows for viewing the valve springs during the operation of the device. The horizontal portion 16 is formed at regular spaced intervals with openings 19 that communicate 60 with slots 20 extending from the inner longitudinal edge of the portion so as to provide entrance passages for inserting the valve stems into the openings 19. Intermediate its ends, the portion 16 is formed with a 65 relatively small opening 16^a beneath which is secured a lug L.

The valve lifting device also includes a spindle designated at S and which is screw threaded for a major portion of its length 70 to receive an adjusting nut N. As shown in Figure 5, the spindle S is bifurcated at one end to provide a pair of relatively long positioning lips 21, while the opposite end is slotted transversely to provide relatively 75 short positioning lips 22.

In Figures 1, 2 and 3, I have shown a portion of a conventional form of internal combustion engine in which one side thereof is formed with the usual chambers designated at C designed for the purpose of 80 gaining access to the valve springs and pins. As usual, the edges of the chamber C are formed with flanges, the upper flange being designated at 28, the lower flange at 28^a and the end flanges at 28^b. The valve stems are designated at 23, and are surrounded by springs 24, the lower ends of which latter 85 repose on seats 25. The valve seats 25 in turn engage the pins 26, and the usual push rods 27 extend inwardly into the chambers 90 and are associated with the valve stems in the manner shown.

In the applied position of the valve lifting device to either of the chambers C, the yoke Y is applied to the valve stems 23 so that the latter are disposed within the openings 19, it being understood that the stems pass through the entrance passages 20 to enter the openings. As so applied, the horizontal portion 16 of the yoke is interposed 95 between the upper end of the push rods 27 and the seats 25 in the manner clearly shown in Figures 2 and 3. The diameter of the openings 19 exceeds the length of the pins 26 so with the yoke in applied position to the seats 25, the pins 26 are not engaged by the horizontal portion 16 of the yoke thus 100 allowing the free upward movement of the yoke without engaging the pins. In the 110 applied position of the yoke, the spacing blocks 17 engage the flanges 28^b and thus

maintain the vertical portion 15 in definite spaced relation to the springs 24 of the valves so that the yoke can move forwardly without contacting with the valve springs.

- 5 In the application of the spindle S, it is inserted through the lug L and the opening 16 and moved to occupy a vertical position so that its upper positioning lips 21 engage the upper flange 28 while its lower lips 22 10 engage the flange 28^a thereby rigidly securing the spindle in vertical position. With the nut N positioned upon the spindle as shown in Figures 1 and 3, it will, when rotated in the proper direction, effect the elevation of the yoke as a whole thereby causing the portion 16 to engage and lift the several valve spring seats 25. After the yoke has been moved from its initial position to its upper and final position as shown 15 in Figure 1, the springs 24 have been completely compressed so that the pins 26 are now free to be withdrawn from the valve stems. It is to be particularly noted that all of the valve spring seats can be held in 20 elevated position without necessitating the manual holding of any part of the device so that the operator's hands are free to withdraw the pins. Furthermore, the compression of the several valve springs is uniform 25 throughout so that the normal tension of the springs is maintained thus insuring the proper operation of the valves when the springs are again extended and moved into 30 normal position.
- 35 In Figure 6 I have shown a suitable form of wrench adapted to effect rotation of the nut N. This wrench is designated generally at W and includes an open ended socket 29 formed on one end of a handle 30.
- 40 Although I have herein shown and described only one form of valve lifting device and wrench, each embodying my invention, it is to be understood that various changes and modifications may be made 45 herein without departing from the spirit of the invention and the spirit and scope of the appended claims.
- What I claim is:
- 50 1. A device for simultaneously compressing a plurality of valve springs, which consists of a yoke inclusive of vertical and horizontal

plates, the horizontal plate being provided with valve stem receiving openings and the vertical plate being provided with sight openings affording a view of the spring and the valve stem, a vertical spindle extending through said horizontal plate and having its ends slotted to define pairs of attaching lugs adapted to securely engage portions of the engine whereby to hold the spindle against rotation, and an adjusting nut threaded on said spindle and adapted for holding the yoke in a set position whereby the valve springs may be held compressed during removal and attachment of the valve. 55

2. A device for simultaneously compressing a plurality of valve springs, which consists of a yoke inclusive of vertical and horizontal plates, the horizontal plate being provided with valve stem receiving openings, a vertical spindle extending through said horizontal plate and having its ends provided with pairs of attaching lugs adapted to securely engage portions of the engine, and an adjusting nut threaded on said spindle and adapted for holding the yoke in a set position whereby the valve springs may be held compressed during removal and attachment of the valve, the vertical plate of said yoke extending beyond the horizontal plate whereby to form a means for holding the yoke against transverse tilting. 70

3. A device for simultaneously compressing a plurality of valve springs, which consists of a yoke inclusive of vertical and horizontal plates, the horizontal plate being provided with valve stem receiving openings and the vertical plate being provided with sight openings affording a view of the spring and the valve stem, a spindle extending through said horizontal plate and provided with pairs of attaching lugs adapted to securely engage portions of the engine, an adjusting nut threaded on said spindle and adapted for holding the yoke in a set position whereby the valve springs may be held compressed during removal and attachment of the valve, and spacing blocks carried by the ends of said vertical plate and forming 80 a means to hold the yoke against transverse tilting. 85

ALBERT LOVELESS.
